Primary Examiner — Katherine Glennon*Assistant Examiner* — Yuan Yuan(57) **CLAIM**

The ornamental design for a 3D-interlocking puzzle, as shown and described.

DESCRIPTION

1. 3D-interlocking puzzle

1.1 is an exploded perspective view.

1.2 is a perspective view.

1.3 is another perspective view.

1.4 is a perspective view shown without the detachable puzzle pieces.

1.5 is another perspective view thereof.

1.6 is a perspective view showing only the detachable puzzle pieces.

1.7 is second perspective view thereof.

1.8 is a third perspective view thereof, and

1.9 is a fourth perspective view thereof.

The characteristic features of the design lie in the shape of the puzzle game and puzzle pieces as shown; the other views of the completed puzzle as shown in view 1.2 and 1.3 are omitted because they are identical or mirror images of the perspective views 1.2 and 1.3.
